UNITED STATES PATENT OFFICE

113,570

DESIGN FOR A VENETIAN BLIND TILTER

Aaron A. Radel, New York, N. Y., assignor to Master Venetian Blind Hardware Corporation,
New York, N. Y., a corporation of New York

Application November 23, 1938, Serial No. 81,307

Term of patent 7 years

To all whom it may concern:

Be it known that I, Aaron A. Radel, a citizen of the United States, residing at New York, county and State of New York, have invented a new, original, and ornamental Design for a Venetian Blind Tilter, of which the following is a specification, reference being had to the accompanying drawing, forming part thereof.

Fig. 1 is a side elevation of the Venetian blind tilter showing my new design.

Fig. 2 is a rear view and

Fig. 3 is a front view of the same.

I claim:

The ornamental design for a Venetian blind tilter, substantially as shown.

AARON A. RADEL.
